IMPROVEMENT IN THE MANUFACTURE OF SHEET-METAL BOXES.

ALFRED BARNES, OF WILLIAMSBURG, NEW YORK.

Letters Patent No. 59,942, dated November 27, 1866.

SPECIFICATION.

TO ALL WHOM IT MAY CONCERN:

Be it known that I, ALFRED BARNES, of Williamsburg, in the county of Kings, and State of New York, have invented a new and useful Improvement in the Manufacture of Sheet-Metal Boxes; and I do hereby declare that the following is a full, clear, and exact description thereof, which will enable those skilled in the art to make and use the same, reference being had to the accompanying drawings, forming part of this specification, in which—

Figure 1 represents a plan of the blank.

Figure 2 is a plan of the same after it has passed through the first operation necessary to produce the edges.

Figure 3 is a transverse section of the same.

Figure 4 is a transverse section of the box when ready.

Similar letters of reference indicate like parts.

This invention relates particularly to that class of sheet-metal boxes which are made in cook form, and which are mostly used as lunch boxes. The invention consists in constructing the side pieces, and bottom or top of the box, out of one piece, by cutting out a blank of the required shape, and turning the side pieces up gradually, in such a manner as to produce the required arms or flanges, and so that a box is obtained of superior strength and durability, and less expensive in labor than a similar box of the ordinary construction. A represents the blank which is intended for the body of my box. The shape of this blank is best seen in fig. 1. In order to bring this blank in the requisite form, the edges are turned over, and the back and front are curved, and then those edges, where the side pieces join the bottom, are turned up, by a suitable die or any other convenient means, to the form shown in figs. 2 and 3. After this has been accomplished the blank is exposed to the second operation, which consists in turning the edges down to the position shown in fig. 4. This operation is carried out by means of a suitable tool, which catches over the edges, and turns the same down to the required position, and which may be operated by hand or by suitable mechanism, or said operation may be performed entirely with the hammer, although in practice the use of a suitable die or tool is preferable, because it saves much time, and produces better work. By these means the rims; *a*, on the front and ends of the box are obtained in the desired form, and said rims or flanges are strong and durable, and no soldering is required in order to fasten the side pieces to the bottom. The top or cover, *B*, of my box may be made in the same manner as above described, leaving the side pieces shorter than those of the body of the box, as shown in fig. 4, or said cover may be made in the usual manner. It is obvious that a box of this description can be made of any suitable material, although the same will be generally made of trimmed sheet iron.

What I claim as new, and desire to secure by Letters Patent, is—

The struck-up flanged sides of the body *A*, of the shape herein described, for the purpose specified.

ALFRED BARNES.
